Richardson Atty.

UNITED STATES PATENT OFFICE.

JOSEPH J. BABKA, OF BERWYN, ILLINOIS.

MIXING MACHINE.

Application filed February 7, 1924. Serial No. 691,126.

To all whom it may concern:

Be it known that I, JOSEPH J. BABKA, a citizen of the United States of America, and a resident of Berwyn, county of Cook, and State of Illinois, have invented certain new and useful Improvements in Mixing Machines, of which the following is a specification.

My invention relates in general to mixing machines, such as are used for mixing or blending different materials; and the object is to provide a new and improved device of this character, having numerous advantageous features tending to enhanced usefulness and efficiency.

More specifically, I have devised a mixing machine which is especially adapted for dry mixing any specified materials in finely divided or powder form, usually as a step in some process in which such materials are to be compounded into a given product. As stated, any materials whatever may be handled, the only requirements being that they be reasonably dry and in a more or less finely divided or comminuted state. As an example of a specific use to which the mixer is well adapted, may be mentioned the mixing of sand and cement as a step in the process of producing mortar or concrete. Another example, in a different art, is the mixing of chemicals in powder form, perhaps as a step in some manufacturing process, or in the compounding of prescriptions by apothecaries, the size of the mixer being of course suited to the use.

In accomplishing the desired results I employ a simple but very effective arrangement comprising essentially a plurality of superimposed screens, a plurality of interposed baffles, suitable means by which these parts are assembled into a complete mixer, and means for vibrating the mixer at a high frequency, which in its preferred form is a high speed unbalanced revolving shaft.

One particular embodiment of the invention is shown in the accompanying drawings, in which:—

Fig. 1 is a top view of a heavy duty duplex mixer, the right hand bank of screens

having been removed, however, in order to more clearly show the construction of the vibrating frame;

Fig. 2 is a side view of the mixer shown in Fig. 1; while

Fig. 3 is a cross section through the bank of screens on the line A, Fig. 2.

Referring to the drawings, and particularly to Figs. 1 and 2, the main frame may be of any appropriate design depending on the particular situation, but as shown herein comprises two heavy sill pieces, one of which is indicated in Fig. 2 by the reference character 2. These sills are secured together by cross pieces 3 and 4, which also serve as a convenient support for the vibrating frame above. The latter consists essentially of two side pieces 5 and 6, of somewhat lighter material than the sills, two end pieces or spacers 7 and 8, two intermediate spacers 9 and 10, two end cross pieces 11 and 12, corresponding to cross pieces 3 and 4 on the main frame below, and two intermediate cross pieces 13 and 14. The various parts enumerated are fastened together in any convenient manner, although preferably this is done with screws.

The upper or vibrating frame is supported on springs, four in number, which are interposed between the cross pieces 3 and 4 on the lower frame, and cross pieces 11 and 12 on the upper frame. Two of these springs may be seen in Fig. 2 where they are indicated by reference characters 15 and 16. Associated with the four springs are four centering bolts 20, 21, 22, and 23. These bolts are rigidly attached to cross pieces 3 and 4 by nuts above and below, and pass thru loose fitting holes in cross pieces 11 and 12. A large square iron washer may be inserted above and below each spring to provide a suitable bearing surface, as indicated in the drawing Fig. 2.

The means for vibrating the upper frame comprises a transverse shaft 25 supported on bearings 26 and 27 rigidly secured to the frame. The shaft is unbalanced to any necessary degree by adjustable weights 28 and 29. Power may be supplied from any

suitable source, such as a small motor belted to the shaft. Pulley 30 is provided for this purpose.

Referring now to Fig. 3, which as stated 5 is a cross section through a complete mixer removed from the vibrating frame, the construction of the mixer may be explained. It consists essentially of a series of separate 10 rectangular units or frames of any desired number, although nine are shown, each having a screen and a series of baffles, together with a lower frame having a screen only, and an upper frame having neither screen nor baffles and forming a hopper. 15 The lower frame is indicated by reference character 35. The associated screen 36, preferably of wire screen cloth, is secured to the upper edges of the frame members by braces, staples, or any suitable means. 20 The other frames are similar to frame 35, although of greater depth. Considering the next one up, the frame proper is indicated by reference character 37 and the attached screen by 38. The baffles are five in 25 number. The three inside baffles in cross section are like an inverted V while the two outside ones are flat, as shown, and all five extend across the frame below the screen. To support the baffles two notched strips 30 are attached to two opposite frame members on the inside of the frame. The strip attached to the rear frame member of frame 37 is indicated by reference character 39. This strip of course supports the baffles at 35 the rear and they are supported in front by a similar strip attached to the front frame member.

Frame 40 is like 37 except that the baffles are six in number, as shown, arranged alternately with the baffles in frame 37. Frames 41 and 43 are exactly like 37, while 42 is like 40. The other frames are like the ones shown but are rotated 90° so that the baffles are at right angles to the baffles in the frames 45 just described. Thus frames 44, 45, 46, and 47 correspond, respectively, to frames 40, 41, 42 and 43. It is noted that in the case of frames such as 44 and 45 the supporting strips for the baffles are seen in section, and 50 their relation to the frame members and baffles is perhaps more clearly indicated than in the case of frame such as 37 where a side view of one strip only is obtained. Reference characters 48 and 49 indicate the supporting strips in frame 44, and 50 and 51, those in frame 45.

The arrangement for mounting the mixers on the vibrating frame of the machine can best be explained with reference to Fig. 1, 60 where it will be seen that side members 5 and 6 and spacers 8 and 10 form a rectangular enclosure the inside dimensions of which, it may be stated, are the same as the outside dimensions of the mixer frames. Similarly, 65 at the other end the spacers 7 and 9 coop-

erate with the side members to form a second enclosure. In order to provide a solid support for the mixer frames, rectangular bases are placed in these enclosures. The bases are indicated by reference characters 70 55 and 56. Base 55 is shown in Fig. 1 where it can be seen resting on cross pieces 13 and 11.

To assemble the mixer, frame 37 is placed on base 56 and the remaining frames are 75 stacked up in order, as shown in Fig. 2 at the left. The assembled frames are then clamped together by means of cross members 60 and 61 and four clamping bolts 62, 63, 64, and 65. These bolts are each formed with 80 a hook on the lower end which engages the lower edge of the adjacent frame member such as 5 or 6. A similar mixer may of course be assembled at the right on the base 55.

The arrangements for conveying the materials to the mixing machine and for handling the product may be of any suitable form known in the art. For instance, the machine may be located over a bin for receiving the mixed materials and the separate materials may be delivered by belt conveyors, all preferably delivering into a common discharge spout arranged to discharge the materials at the center of the top screen 95 of mixer. All materials are of course pre-sized so that no large particles will be presented which are unable to pass the screens of the mixer.

The operation will doubtless be obvious 100 in view of the detailed explanation of the construction but may be briefly explained as follows: Assuming that the motor has been started, the rapidly revolving shaft 25, unbalanced by weights 28 and 29, will cause the spring supported frame carrying the mixers to vibrate. The vibrations, it may be stated, are of small amplitude but of high frequency, the speed of the shaft being 105 preferable in the neighborhood of 1800 R. P. M. As the materials are delivered to the mixer they spread over the surface of the top screen and the feed is adjusted to a point where the surface of the top screen 110 is about two thirds or three quarters covered. A temporary increase in rate of feed will then be taken care of automatically, for the rate at which the materials pass through the top screen of course depends 115 on the amount of surface covered. The top screen is preferably of slightly smaller gauge than the remaining screens to avoid any possibility of choking lower down.

On passing the top screen the materials are 120 deflected by the baffles to form four relatively thin streams each of which is composed of materials coming through two different sections of the top screen. These streams are deposited in ridges on the second screen 125 where they spread out to some extent before 130

passing through. On reaching the next series of baffles the materials from different sections of the screen are again combined into four streams, this time, however, the 5 deflections being at right angles to the deflections caused by the upper baffles. That is, the streams of material flowing through the openings between the second series of baffles, those in frame 47, are deposited in 10 ridges which extend across the third screen in a direction parallel to the plane of the drawing. The materials now spread out over the third screen, eventually pass through, and are again formed into streams by the 15 third series of baffles. The third set of baffles, it will be observed, are staggered with respect to the first set, so as to provide for combining materials from two different openings in the upper series of baffles. The 20 process from this point on is a repetition of what has already taken place. The materials are deposited on the remaining screens in order, being deflected first in one direction and then in the other by the associated 25 baffles and eventually pass through the last screen in a thoroughly mixed state.

The mixing action takes place through two main agencies, the screens, on which the materials spread out before passing through 30 and become mixed more or less, and the baffles, which unite materials from different screen sections of the screens above, or looking at it in a different way, each of which divides the materials coming through a given 35 section of the screen above into two streams and combines each of these with another stream deflected by the adjacent baffle.

It will be understood of course that the 40 duplex construction is simply a convenient method of utilizing a single vibrating shaft, and that one mixer alone or more than two could be mounted on the same frame. When using a plurality, they may work series or parallel, the former arrangement being 45 adopted where an exceedingly intimate mixing is desired. For series working a suitable elevator must be provided to transfer the material from one end of the machine to the other, unless two complete machines are 50 used, in which case they may be mounted one above the other so that the top machine can feed directly into the lower one.

While I have shown a certain specific construction, including a certain specific arrangement of the screens and baffles, I am 55 aware that modifications may be made and that the various parts may be rearranged or otherwise altered to a considerable extent without departing from the principles of my invention; I do not therefore wish to be limited to the precise form of my invention shown and described, but desire to include and have protected by Letters Patent all 60 forms of my invention which come within the scope of the appended claims.

What I claim is:

1. In a mixing machine, a series of superimposed screens, sets of baffles interposed between adjacent screens each set being so arranged as to divide the material and deflect 70 part in one direction and part in another, a supporting frame, and means for vibrating said frame.

2. In a mixing machine, a frame, a plurality of horizontal screens supported one 75 above the other on said frame, means for preventing materials from flowing off the edges of said screens in any direction, and means for vibrating said frame,

3. In a mixing machine, sets of baffles arranged in echelon, and means interposed between adjacent sets of baffles for temporarily arresting the flow of and redistributing the materials. 80

4. In a mixing machine, a series of superimposed vibrating screens, and means inserted between each pair of adjacent screens for dividing the material passing through the upper screen of the pair and for diverting 85 part in one direction and part in another. 90

5. In a mixing machine, a series of superimposed vibrating screens, and means for diverting the flow of material from a given section of any screen to two non-corresponding 95 sections of the screen below.

6. In a mixing machine, a vibrating frame, a series of baffles all in the same plane extending across said frame, a second series of baffles extending across said frame in a different plane and in a different direction, 100 and means for temporarily arresting the flow of material from the first series of baffles to the second.

7. In a mixing machine, a vibrating frame, a series of baffles supported on said frame, 105 a second series of baffles supported on said frame in a position at right angles to and below said first series, and a screen interposed between said series of baffles.

8. In a mixing machine, a vibrating frame, groups of baffles supported on said frame, the baffles of each group lying in a different plane, other groups of baffles arranged alternately with the said first mentioned groups and supported on said frame 110 so as to divert the material in a different direction from that in which it is diverted by the baffles of said first groups, and means interposed between adjacent groups of 115 baffles for redistributing the material. 120

9. In a mixing machine, a vibrating frame, a series of superimposed screens supported on said frame, sets of baffles supported on said frame in certain of the spaces between said screens, and other sets of baffles disposed at an angle horizontally to the baffles of said first mentioned sets and supported on said frame in certain other spaces between said screens. 125

10. In a mixing machine, a vibrating 130

frame, three screens supported on said frame one above the other, a baffle positioned between the top and middle screens to divert a portion of the material passing through the top screen, and a second baffle positioned between the middle and lower screens at an angle horizontally to said first baffle to divert a portion of the material passing through the middle screen in a different direction.

11. In a mixing machine, a vibrating frame, a plurality of screens spaced apart and supported on said frame one above the other, sets of baffles arranged in echelon and positioned in alternate spaces between screens, and other sets of baffles also arranged in echelon and positioned in the remainder of the spaces between screens at an angle to the baffles of said first mentioned sets.

12. A mixing machine comprising a plurality of screen frames stacked up one above the other and secured together, a set of baffles extending transversely across each frame, and a screen stretched on each frame above the associated baffles.

13. A mixing machine comprising a plurality of screen frames stacked up one above the other and secured together, a set of baffles extending transversely across each frame, and a screen stretched on each frame above the associated baffles, each frame being turned 90° with respect to the one below so that the baffles of adjacent sets stand at right angles to each other.

14. The process of mixing different materials which consists in flowing the materials by gravity in a plurality of streams in different directions, in changing the composition of the streams and the direction of flow of all the material a plurality of times, and in arresting the flow temporarily each time before the direction is changed sufficient to destroy the preceding stream formation.

15. The process of mixing materials which consists in forming and reforming all the material in successive pluralities of thin streams, the streams of each plurality being each composed of materials from all the streams of the preceding plurality, and in arresting the flow before each plurality of streams is formed sufficiently to destroy the preceding stream formation.

16. The process of mixing materials which consists in flowing the material by gravity in a substantially vertical direction, in dividing the flow stream into a plurality of flow streams, in combining adjacent streams in pairs, in arresting the flow temporarily to destroy the stream formations and change the relative position of adjoining particles, and in again dividing and combining as before except that the lines of division are

angularly displaced from the lines along 65 which the first divisions were made.

17. In a mixing machine, a plurality of superimposed screens, means located in one space between adjacent screens for diverting the flow of material in two directions, and means located in another space between adjacent screens for diverting the same material in two different directions.

18. In a mixing machine, a plurality of superimposed screens, and means located beneath each screen for concentrating the material flowing through into a plurality of streams.

19. In a mixing machine, a plurality of superimposed screens, means located in one space between adjacent screens for concentrating the material flowing through the screen above into a plurality of streams extending transversely across the machine, and means located in another space between adjacent screens for concentrating the material flowing through the screen above into a plurality of streams extending transversely across the machine in a different direction.

20. In a mixing machine, a vibrating frame, a series of baffles extending across said frame all in one plane, said baffles being spaced close together so that the space between adjacent baffles is much less than the width of each baffle, whereby material delivered from adjacent baffles mingles together in a common stream, and a second series of baffles similar to said first series extending across said frame in a different plane and in a different direction.

21. The process of mixing different materials which consists in flowing the material by gravity, in dividing the flow into a plurality of streams, in combining adjacent streams and in then forming the material into a relatively large plurality of minute streams, and in again dividing the flow into a plurality of streams each of which is composed in part of material from each of the streams of the first plurality.

22. In a mixing machine, a series of screens positioned one above the other, the openings in each of said screens being large enough to pass all of the material, means for vibrating said screens to cause material supplied to the upper screen to flow through all said screens successively, and means for diverting the flow of material from the perpendicular between adjacent screens.

23. In a mixing machine, a series of screens positioned one above the other, the openings in each of said screens being large enough to pass all of the material, means for vibrating said screens to cause material supplied to the upper screen to flow through all said screens successively, and means inserted beneath each of a plurality of said

screens for forming the material into said screens successively, means located beneath one of said screens for forming the streams.

24. In a mixing machine, a series of screens positioned one above the other, the openings in each of said screens being large enough to ultimately pass all the material but small enough to appreciably delay the flow and cause the material to accumulate on the screens, means for vibrating said screens to cause the material to flow through

said screens successively, means located beneath one of said screens for forming the material into a plurality of streams, and means located beneath another and lower screen for again forming the material into streams each of which is composed of material from each stream of the first plurality.

Signed at Chicago, county of Cook and State of Illinois, this 2d day of Feb., 1924.

JOSEPH J. BAPKA.
